UNITED STATES PATENT OFFICE.

ROBERT WALKER, OF LONDON, ENGLAND.

BUILDING CONSTRUCTION.

SPECIFICATION forming part of Letters Patent No. 565,580, dated August 11, 1896.

Application filed August 24, 1895. Serial No. 560,418. (No model.)

To all whom it may concern:

Be it known that I, ROBERT WALKER, a subject of the Queen of Great Britain and Ireland, residing at Birkenhall, Stafford, London, in the county of Essex, England, have invented certain new and useful Improvements in Building Construction; and I do hereby declare the following to be a full, clear, and exact description of the invention, such as will enable others skilled in the art to which it appertains to make and use the same.

This invention has for its object to enable structures such as a wall, partition, conduit, or the like to be readily built up with smooth and even surfaces and, if desired, without the aid of cement or mortar; and it consists, essentially, in forming the walls of the structure of bricks or slabs adapted to interlock with one another, so that by arranging the sets of bricks or slabs to break joint with one another in every direction a continuous rigid structure is built up.

The structure may be formed solid of such bricks or slabs, or hollow, and the hollow parts can be filled with cement, concrete, or mortar.

In the accompanying three sheets of illustrative drawings, Figure 1 is an isometric view of a hollow wall filled up with concrete constructed according to this invention. Fig. 2 is an isometric view of a wall built up entirely of bricks or tiles. Fig. 3 is an isometric view of a pipe-conduit for sewers and the like; and Fig. 4 is a similar view to Fig. 2, showing a stronger and thicker construction.

Referring to Fig. 1, the faces of the structure are formed by slabs *a*, having dovetailed grooves *b*, with corresponding projections *c* on their back surfaces. The slabs of each face are secured together by grooved blocks *d*, securing in their relative positions two adjacent slabs *a* in one row and another slab *a* situated in the adjacent row and breaking joint with the two slabs. At intervals there are double-grooved blocks *e*, that tie the two faces together. The hollow space between the two faces is shown filled up with concrete.

If desired, only one face of the structure

may be faced with slabs or bricks, which are keyed to the concrete body by single-ended blocks similar to the blocks *e*.

In the arrangement shown in Fig. 2 the structure is built up entirely of slabs *a*, the projections *c* on one slab fitting into the grooves *b* in the adjacent slabs. In this case, also, the slabs of the two faces are arranged to break joint in every direction both vertically and horizontally. The corner-pieces *f* are slightly modified in shape, being of L shape, and are placed alternately in opposite directions, as shown. The corner of each outside piece *f* is formed with a dovetail recess, in which fits a projection on the inside piece *f*. The parts may be rigidly secured by a cement or other fronting.

The circular conduit shown in Fig. 3 is built up of the inside slabs *h* and the outside slabs *l*, which are arranged to break joint both horizontally and vertically. An egg or other shaped sewer can be built up in a similar way with suitably-shaped slabs or bricks.

In the structure shown in Fig. 4 the one face of the wall has the grooves *b* and projections *c* in the slabs *a* arranged horizontally and the other face vertically, and the two faces are keyed together by intermediate bricks *m*.

It will be obvious that the shape and size and proportions of the slabs and bricks can be varied considerably without departing from the nature of this invention, and the grooves *b* may be made larger than the projections, so as to allow space for cement or other binding material.

What I claim, and desire to secure by Letters Patent, is—

1. A building block or brick consisting of a base and equally-spaced dovetailed projections having parallel edges and situated on and extending across one face, the width of the said brick being a multiple of the distance between the center lines of the projections and the projections being equal in size to or less than the grooves left between the projections so as to enable two adjacent courses to be bonded together.

2. A building block or brick consisting of a grooved block the grooves being dovetail in shape and having parallel edges and extending across the block and being equally spaced 5 and of such size that the groove is the same size as or larger than the dovetail projection left between two grooves and the width of the block being a multiple of the distance between

the center lines of the grooves so as to enable two adjacent courses to be bonded together. 10

In testimony whereof I affix my signature in presence of two witnesses.

ROBERT WALKER.

Witnesses:

JOHN F. GAIRNS,
JOSEPH LAKE.
